UNITED STATES PATENT OFFICE.

JESSE I. BOYER, OF READING, PENNSYLVANIA, ASSIGNOR TO READING IRON COMPANY, OF READING, PENNSYLVANIA, A CORPORATION OF PENNSYLVANIA.

SUGAR-MILL.

1,097,842.

Specification of Letters Patent. Patented May 26, 1914.

Application filed December 27, 1913. Serial No. 808,958.

To all whom it may concern:

Be it known that I, JESSE I. BOYER, a citizen of the United States, residing at Reading in the county of Berks and State of Pennsylvania, have invented certain new and useful Improvements in Sugar-Mills, of which the following is a specification.

My invention relates particularly to sugar mills, and my object is to provide an improved construction whereby serious damage will be avoided in case abnormal strains should occur during operation, as for instance through the accidental introduction to the rolls of metal tools or like foreign matter.

The invention is fully described in connection with the accompanying drawings and the novel features are specifically pointed out in the claims.

20 The drawings illustrate my invention as applied to the particular construction of sugar mill shown in my Patent No. 1,044,127, issued Nov. 12, 1912, though obviously applicable to other constructions.

25 Figure 1 is mainly an end elevation of the roll housing of a sugar mill embodying my invention, the specially formed recess caps and journal-box backing device being shown in cross section on the line 1—1 of 30 Fig. 2. Fig. 2 is cross section on the line 2—2 of Fig. 1. Fig. 3 is an outside view of the recess cap. Figs. 4 to 8 are detail views.

In the type of sugar mill shown in the drawings 35 indicates the top roll and 6, 6 the lower rolls, which have their reduced journal ends 8 mounted in end housings 9. Each housing 9 is formed with outwardly opening recesses 21 for the lower rolls and 40 each of the latter is provided with a journal bearing 20 backed by a wedge block 32 slideable upon the horizontal lower wall 31 of each recess 21. A recess cap 26, secured to the housing 9 by means of lugs 27 and 28 45 closes the outwardly opening side recess 21, and an inward extension 25 forms one of the inclined walls for the journal bearing 20. An adjusting screw 30, mounted in the cap 26, controls the sliding wedge block 32.

50 The construction above briefly discussed is more fully shown and explained in my previous patent referred to.

My present invention relates to the construction of these recess caps 26. In the old

construction of these caps the entire strains 55 came upon the lugs 27 and 28 or upon the screw threads of the bolts 30; and when undue strain was brought to bear upon the rolls, caused by the accidental entry of tools or other hard substances to the mill, there was 60 great danger of breaking the housing itself, or at least the recess caps. These breaks caused serious delays as the parts are large and unwieldy, and my present invention provides for carrying these strains without 65 endangering the breaking of either the housing or caps. To this end I provide each of the recess caps with a passage-way in which is mounted the adjusting screw for the journal-bearing wedge-block, and the 70 screw is retained in the cap by bolts designed to carry the normal working strains upon the adjusting screw, but breakable before the strains reach the danger point of breakage of either the housing or cap. These 75 bolts are easily and cheaply renewed and cause a large saving of time and money in making repairs.

As shown in the drawings I form each recess cap 26 with a squared passage-way 70 80 extending entirely through it, and with bolt recesses 71 communicating with said passage-way, these bolt recesses being cored out at the rear to form seats 72 for the T-heads of the retaining bolts 73. Into this 85 squared passage-way is inserted a nut 74, internally screw-threaded to engage the adjusting screw 30. A passage-way cap 75, having bolt holes 76 and a central hole 77 for the screw 30 is strung upon the latter 90 and bolted to the outer face of the recess cap by means of the T-headed bolts 73. The adjusting screw nut 74 bears against this passage-way cap 75, so that any strain upon the adjusting screw 30 is carried by the T-headed bolts 73, and the latter are made of only sufficient strength to sustain all normal strains, but arranged to break when the strains run over the designed normal strain. When such strains do occur and cause the 100 breaking of the bolts they may be easily gotten at and replaced by merely removing the passage-way cap 75 and nut 74, taking out the broken bolts and replacing them with new ones and returning the nut and cap to 105 position. This avoids handling of any cumbersome parts and permits of quickly and cheaply repairing any break. The with-

drawing screw 33 is shown as passing through a central passage-way of the adjacent screw 30.

My device is simple and efficient and easily applied to the recess caps without changing the construction of the mill, and, its parts being lighter and more readily handled, greatly facilitates the running time of the mill by very largely reducing the time required for repairs, and at the same time greatly decreases the costs of such repairs.

What I claim is:—

1. In a sugar mill having a housing provided with an outwardly-opening recess for 15 a lower roll and a journal-box slidable therein; a recess cap secured to said housing and formed with a passage-way, a passage-way cap secured to the recess cap, a journal-box backing device located in said passage-way, 20 and controlling means for said backing device extending through both of said caps.
2. In a sugar mill having a housing provided with an outwardly-opening recess for 25 a lower roll and a journal-box slidable therein; a recess cap secured to said housing and formed with a passage-way, a passage-way cap secured to the recess cap, a journal-box backing device located in said passage-way and retained by said passage-way cap, 30 and a retracting screw for said backing device.
3. In a sugar mill having a housing pro-

vided with an outwardly-opening recess for a lower roll and a journal-box slidable therein; a recess cap secured to said housing and 35 formed with a passage-way, a passage-way cap secured to the recess cap, a nut slidable in said passage-way, and a journal-box backing screw in said nut.

4. In a sugar mill having a housing provided with an outwardly-opening recess for 40 a lower roll and a journal-box slidable therein; a recess cap secured to said housing and formed with a passage-way, a passage-way cap secured to the recess cap, a nut slid- 45 able in said passage-way, and a journal-box backing screw in said nut extended through said passage-way cap.

5. In a sugar mill having a housing provided with an outwardly-opening recess for 50 a lower roll and a journal-box slidable therein; a recess cap secured to said housing and formed with a passage-way, a passage-way cap secured to the recess cap, a nut slid- 55 able in said passage-way, a journal-box backing screw in said nut extended through said passage-way cap, and a retracting screw extending through said backing screw.

In testimony whereof I affix my signature in presence of two witnesses.

JESSE I. BOYER.
